(57) **CLAIM**

The ornamental design for a display screen or portion thereof with graphical user interface, as shown and described.

DESCRIPTION

The sole FIGURE is a front view of a display screen or portion thereof with graphical user interface, showing the new design.

The evenly spaced broken lines in the drawings show an electronic device and portions of the display screen or portion thereof with graphical user interface, and form no part of the claimed design. The dot-dash broken lines in the drawings show a display screen or portion thereof and form no part of the claimed design.

1 Claim, 1 Drawing Sheet
